(57) **CLAIM**

The ornamental design for a side gallery element for a ring, as shown and described.

DESCRIPTION

FIG. 1 is a side elevation view of a side gallery element for a ring showing a new design in an environment of use, wherein the opposite side elevation view is a mirror image thereto.

FIG. 2 is a top perspective view of the side gallery element for a ring.

FIG. 3 is a bottom perspective view of the side gallery element for a ring.

FIG. 4 is a side elevation view of the side gallery element for a ring, wherein the opposite side elevation view is a mirror image thereto.

FIG. 5 is a top view of the side gallery element for a ring.

FIG. 6 is a bottom view of the side gallery element for a ring; and,

FIG. 7 is a front elevation view of the side gallery element for a ring, wherein the opposite rear elevation view is a mirror image thereto.

The broken lines shown in the drawings represent portions of the side gallery element for a ring which form no part of the claimed design and the broken lines in FIG. 1 represent environmental matter.
